UNITED STATES PATENT OFFICE.

BERNARD GRANVILLE, OF CHICAGO, ILLINOIS, ASSIGNOR TO ALBERT G. CORRE, OF CINCINNATI, OHIO.

TYPE-WRITER.

SPECIFICATION forming part of Letters Patent No. 570,433, dated October 27, 1896.

Application filed July 9, 1895. Renewed October 5, 1896. Serial No. 607,967. (No model.)

To all whom it may concern:

Be it known that I, BERNARD GRANVILLE, a citizen of the United States, residing at Chicago, in the county of Cook and State of Illinois, have invented certain new and useful Improvements in Type-writers, of which the following is a specification, reference being had therein to the accompanying drawings.

The invention herein set forth is an improvement upon the machine shown in Letters Patent of the United States patented to me on the 25th day of April, 1893, and numbered 496,304. The general principle of operation of said patented machine is retained in the machine herein described, and my present invention consisting of details of construction and of parts added or changed in form.

The objects sought in this invention are in part the improved operation of the machine and in part cheapness of construction and durability.

My said invention is illustrated in the accompanying drawings, in which the complete machine is shown, as well as the details and features which constitute my invention.

In the drawings, Figure 1 is a plan view with parts broken away. Fig. 2 is a sectional view from front to rear with parts in side elevation. Fig. 3 is a part side and part sectional elevation of the left-hand side of the machine. Fig. 3^a is a view of a detail. Fig. 4 is a rear view of the machine. Fig. 5 is a rear view of the rear type-bar guide-plate. Fig. 6 is a side view of the right-hand frame of the carriage. Figs. 7 and 8 show a plan and side view of the line-space regulator. Fig. 9 is a front view of the front type-bar guide-plate. Fig. 10 is a front view of the ribbon supporting and operating mechanism and parts adjacent thereto. Fig. 11 is a detail view of the manner of attaching the ribbon-spool springs to their spindles. Fig. 12 shows a bottom plan view of the roller-frame of the carriage. Fig. 13 is a detail side view of the tongue for guiding the type-bars and the fixed guide-plate. Fig. 14 shows the blank from which the type-bar links are formed, showing also a bottom plan view of one of the links. Fig. 15 shows details of the stop for the cradle-frame. Fig. 16 is a view of

one of the key-lever links. Fig. 17 is a detail of a key-lever. Fig. 18 shows the manner of fixing the pivot-pins in the type-bar lever and type-bars. Figs. 19 and 20 show in plan and elevation a key-lever, while Fig. 21 is a detail of the end of the key-lever before it is bent to form the finger-piece. Fig. 22 is a detail view of the pressure-roll and its bearings. Fig. 23 is a detail perspective view of the paper-clip. Fig. 24 is a detail perspective view of the escapement-pawls and their operating-wiper.

The frame which supports, directly or indirectly, the working parts is so formed that it may be made of cast metal. It is shown in plan in Fig. 1 and in side elevation in Fig. 2. It has two side bars A, two pairs of posts marked B and C, respectively, and two cross-bars connecting the side bars directly, marked, respectively, D and D'. Between the rear posts C is a connecting-bar E. Between the front and rear posts on each side bar is a reinforcing rib b.

The key-levers 1 are composed of horizontally-arranged plain bars set on edge and turned up at the forward ends, as shown at 2, to support the finger-pieces 3. These levers are notched at the rear ends on the upper edges and fulcrum upon the lower edge 8a of the cross-bar E. A comb 4 is pinned to the front face of the bar E, and in its slits the rear ends of the key-levers are held. Springs 5 have upturned flanges 6 on their free ends, which embrace and bear upon the lower edges of the key-levers and tend to hold the front ends raised in normal position. The fixed ends of the springs are clamped to the rear cross-bar D', as shown at 7. The plungers or type-bars a are reciprocated in direct lines, as in my aforesaid patent, in a rocking frame, in which these bars converge to a common printing-point. The front ends of these bars are connected to the longer arms of bell-crank levers 8 and 9, which are in turn pivoted to posts 10 and 11, and are connected by links 12 and 13 to the key-levers. The lower ends of these posts are notched. These lower ends are fixed in the front cross-bar 15 of the cradle-frame by setting them in the mold and casting the metal around them—this to avoid the expense of drilling and riv-

cting. The links are shown more clearly detached, as in Fig. 16. They are struck out of sheet metal with slots at the ends made to fit over the levers, which they connect. The 5 lower ends of these links are held in place upon the key-levers by special construction. (Illustrated more clearly in Figs. 19 and 20.) When these levers are struck out, spring-tongues *b* are also struck out free at one end 10 and left integral with the metal at the other end. These are reversed to each other, the free ends being directed toward each other, with a space between to receive the link, which is slipped on over the tongue into the 15 space in which it is held. This accurately locates and holds the link, and depression of the lever pulls down the short arm of the bell-crank lever and projects forward the type-bar.

20 The front ends of the type-bars are connected to the bell-crank levers by a special form of links 16. These are struck out of sheet metal in the form shown in Fig. 14. These blanks are bent on the line *m n*, 25 equally dividing the intermediate part 17, and when thus bent the sides and projecting ends are separated by a space sufficient to admit the edge of the type-bar. The end of the lever-arm is provided with a pin 18 fixed 30 therein and projecting on each side, and a similar pin is in the forward end of the type-bar at 19. The holes 19' in the link are fitted to these pins, and connection is made by spreading the ends of the link and allowing 35 them to spring back over the pins. The bent part 17 rests on the upper edge of the type-bar when the parts are in normal position, and the forward end of the link rises when the key-lever is operated to impel the bars. 40 The parts are returned to normal position by the spring 5.

The backward movement of the bell-crank levers is limited by a stop 20, composed of a 45 rod held upon arms and incased preferably in rubber tubing. A similar stop 21 lies across the upper surface of the key-levers and limits their return movement. This stop lies just in rear of the upturned ends of the key-levers.

50 In order to form inexpensively the finger-pieces on the ends of these levers, these ends are made in the stamping of the lever, as shown in Figs. 19 and 21. The end is cut approximately in the form of a circle, leaving a 55 nearly complete disk 22, with slits 23, which partially sever the disk from the end of the bar, leaving a narrow neck 24, which, when the disk is turned up at right angles to the neck, as shown in Fig. 17, leaves the neck 60 connected with the center of the disk, which forms the base of the cap. The cap is completed, as shown in section in Fig. 20, by placing on the disk another disk 25, which is held in place by a thimble 26, forced down over the edge of the disk 22.

The general principles of construction and operation of the cradle which carries the type-

bars is the same as in my aforesaid patent of 1893. It differs, however, in details. The base of the frame is the transverse bar 15, in 70 which the posts 10 and 11 are embedded. The arms 28 are cast in one piece with the standard 28' and the base-bar 15. Across the rear ends of the arms 28 is fixed another casting consisting of two curved bars 29 and 30, 75 on the ends of which are posts 31 and 32. This casting is held upon the arms 28 by a screw at each end, and upon it are fixed guide-plates 33 and 34. These plates are pierced for the passage of the type-bars, the 80 holes in the plates forming guides for the bars. These plates may be made of hardened steel, so as to resist the wear. The main frame of the cradle is formed with two arms 35 extending from the end of bar 15 forward 85 on each side of the bank of keys, and on their forward ends they have finger-pieces 36, by means of which the cradle may be tilted to bring the caps into alinement. The rear end of the cradle is down normally, so that the 90 upper row of characters is normally in alinement with the printing-point. When the lower rows are to be brought into alinement, the cradle is tilted by pressure upon the finger-piece 36 on either side of the bank of keys. 95 On the left side I have provided a locking device consisting of a pivoted arm 38, which has a stud 39 and is held by a spring 40. The arm is so arranged that when it is tipped forward it is out of connection. When it is 100 tipped back, the stud 39 strikes a stud 44 on the arm 35 on the left side, and thereby throws down the arm 35 and locks the cradle with the lower row of type (usually capitals and character less used) in range with the printing-point. The connection with the spring 105 shown in Fig. 2 holds the arm 38 in both positions.

The cradle is pivoted at 45, and requires but slight movement. The pivot being near 110 the front end of the cradle, its rear end drops by gravity, which I have found to be the best mode of returning it, as I thereby avoid the rebound of a spring.

The movement of the cradle is limited by 115 stops 46 and 47. The stop 48' consists of the upturned rear edge of the plate 48. On an arm extending downward in rear of the stop 48' is a buffer 49, clamped under an eccentric disk 50, held by a screw 51, which presses the 120 disk into the leather. The amount of motion permitted the cradle may be regulated by loosening the screw and turning the disk thereon. The stop 47 is a projection on the cradle-frame, with projection and buffer 52, 125 which is constructed and held adjustably the same as the buffer 49.

In rear of the cradle, and between it and the printing-point on the type-cylinder K, are 130 guide-plates 53. These are supported upon a stud 54 on the main frame. The plates converge to the printing-point, leaving a space between their rear ends for the passage of the heads of the type-bars. The arrangement

of the plates is shown more clearly in Figs. 2 and 10. The ends of these plates are close to the face of the cylinder which carries the paper and serves as a platen. It will be observed that the type-bars converge, but carry the heads on which the type are set arranged squarely to the platen, so that the type may be impressed in lines at right angles to the surface of the paper. In order that the blow may be delivered in the same direction, I have provided a central guide consisting of the plate 55. This plate is hung so as to swing freely within the narrow limits permitted by the guide-plates 53, between the forward ends of which the central guide projects. The central guide may be thrown from side to side, according as the right or left hand type-bars are brought into action. The central guide-plate is loosely connected on the central vertical line with the plate 33, and whether the right-hand type-bars or the left-hand are in action the central plate forms the auxiliary guide on one side and one of the fixed guides 53 serves as the guide on the other side. These guides being properly adapted to the heads on the type-bars, they accurately direct the type to the printing-point. This guide is lateral, but as the bearings in the curved plates are widely separated, the type have accurate lineal alinement from those bearings. On whichever side the type-bars are acting, the guides cause the type in its final movement to strike squarely against the paper.

I have changed the construction of the frame which supports the connecting ribbon on both sides of the printing-point and raises and lowers it so as to interpose the ribbon when the impression is made, and to lower the ribbon when the type-bar is withdrawn. This frame I have shown as struck up out of thin sheet metal. It is shown at 0 in Figs. 1 and 10. Part consists of two long arms 60, having bearings 61 in standards 61', on which they move. These arms converge to the front ends of the guide-plates 53. At this point they are formed on one side with a wing 62, which, when the frame is down, rests on the top of the guide-plates, and in this position the ribbon is below the line of print. The arms extend backward to the points 63, from which points it forms a bow 64, with arms 65, which are turned up to make a loop for holding the ribbon. There is a similar loop on each of the arms, at 66, and the ribbon is led from the spools through the loops 66 and 65 and across the loop 65 on the other side, and so back to the other spool.

On each end of the frame 0 is rearwardly extending arm 67, made preferably of steel wire, which extends to the rear of the pivot and forms the lever-arm by means of which the frame is raised to bring the ribbon over the printing-point. These arms are connected by rods 68 with a transverse bar 69, which lies under and across the key-levers, so that on every depression of the key-levers

the ribbon is raised and the parts are so adjusted that the ribbon rises into place before the type-bar has delivered its blow. A light spring 70 returns the frame and ribbon to their low position, thus disclosing the character which has been printed. The shafts 71, which carry the spindles for the spools, are mounted in vertical bearings in the main frame and have beveled gears 72 in mesh with other beveled gears 73 on the horizontal shaft 74, also mounted in bearings in the main frame. The shaft is longitudinally adjustable and the gears 73 are separated, so that upon shifting of the shaft 74 either one or the other may be thrown into mesh, so that the ribbon may be fed in either direction by simply pushing the shaft. The shaft 74 is turned by means of a bevel-gear 75 meshing with another bevel-gear 76 on a shaft prolonged from the axis of the escapement-wheel, which permits the carriage to move to the left in printing the line.

The spools are made of disks 77, struck up out of thin sheet metal and connected by sleeves fitted to admit a spindle. For convenience and economy I make the spindle 78 of the same diameter as the shaft which carries the beveled gear 72, and I support this shaft in its bearings by a small collar 79, which is forced down over the spindle. The spool is held by the frictional contact of a spring 80, which is made in the form of a bow and set in a slot milled longitudinally in the spindle, the spring being held by pinching the walls of the slot against the spring.

The carriage-bed is formed of a separate casting consisting of a frame formed of side bars 81 and 82, connected by cross-bars at the end, the side bars being planed out to form guideways for the trucks on which the carriage moves. The front bar of this bed is made higher and upon it are formed the arms which carry the bearings of the spool-shafts, and also the arms which support the driving-shaft for the spool. The carriage-frame has end pieces formed of castings, as shown in Figs. 2 and 6. The main connections between these end frames consist of the rack-bar 84, fixed to the rear leg 85, and a rod 86, fixed to the front leg 87. The right-hand bearing for the paper-roll K is at the point 89, being a simple hole opening inwardly. The left-hand bearing 90 is an open slot, in which the shaft is held by one of the springs 91, it being thus made removable easily. The pressure-roll 92 is set in bearings in spring-arms 93, pivoted on the inner faces of the end frames. The springs 93' of these arms are controlled by set-screws 95. In front of this roller, on the same arms, is fixed a thin bar 94, beveled to fit the contour of the paper-roll.

In rear of the pressure-roller is a curved plate or paper-shelf 96, the ends of which are supported by bearing against the ribs on the end frames, being held in place by the clips 97 98, which are bent to bear on the lower side of the shelf at X, and have forward ex-

tensions engaging the shelf. For convenience of construction the clips 98 are turned over the bar, and so held thereon, and, extending underneath, are turned up to form the front 5 springs, which guide the paper in front of and over the roller. On the right-hand clip 98 is pivoted the dog 99, which trips the bell-hammer.

The ratchet-wheel, by means of which the 10 paper-roll is turned for line-spacing, is on the right-hand end of the roller. It is operated by a pawl 100, which has a tooth 101 arranged to engage with the ratchet-wheel. The pawl extends up between stop-arms 102, cast upon 15 an arm 104 on the right-hand end frame. The pawl is pivoted upon the end of the frame 105, the arms of which are pivoted at 106 on the inner face of the end frames. The pawl is held in engagement and at the same 20 time pulled back after action by means of diagonally-arranged spring 107. The arm of the frame 105, on the left hand, extends to the rear, as shown at 108, and engages with a bell-crank lever 109, pivoted on the end 25 frame. Against the lower arm of this bell-crank lever bears the end of a freely sliding rod 110, the right-hand end of which is arranged to strike upon an adjustable stop 111, set on a rack-bar 112, fixed to the rear of the 30 main frame of the machine. The sliding rod is held in guides 113 114, the latter being in the end of the arm 115, through which the carriage is moved. When the rod strikes the stop, it operates the frame through the 35 bell-crank lever, causing the pawl to rise and move the paper-roller one notch, so that this movement is caused by the return movement of the carriage, and the shock of the stop is taken up in the work done by the pawl and 40 the tension of the pawl-spring. To vary the space, I have provided a line-space regulator, and for economy of construction this is made of special shape. It consists of a piece of 45 sheet metal cut out in the shape shown in Figs. 6, 7, and 8. It has a pivot-hole 116, and in the same plane with the part having this pivot-hole an arm turned up to form a 50 guide for the tooth of the pawl. Another arm 117 is bent over the arm 104 of the end frame, and on the end of this bent arm 117 are two stops 117^x, which limit the upward and downward movement of the arm 117. A 55 pin 118 engages with the arm 117, which springs over the pin and holds it in raised position. The pin projects from the arm 104, and the arm 117 has an opening, Fig. 8, to engage the pin. This piece is pivoted upon a shoulder in the frame around the bearing 60 of the paper-roll.

60 The line-space regulator has a curved edge 117^a concentric with the teeth of the ratchet and projecting sufficiently to form a rest for the pawl-tooth 101 to rest against, and thus be held out of engagement with the ratchet, 65 and by adjusting this line-space regulator to its extreme position more or less of the ratchet-teeth will be exposed to be engaged

by the pawl, the edge acting as a shield during part of the movement of the pawl.

The arm and lever for moving the carriage 70 are substantially like those in my aforesaid patent. The part directly underneath is in the form of a bell-crank lever, marked 119. It is pivoted near the front of the machine at the angle, and the shorter arm extends across 75 the machine and is connected to an arm 120 on the shaft 121 in the forward posts B. This shaft has arms 121^x with finger-pieces upon the ends extending to the side of the keyboard, so as to be within reach of the operator without removing his hands from the keyboard. There is one arm at each end of the shaft, so that the carriage may be moved by either hand. The long arm of the bell-crank lever extends to the rear and is 80 connected by a link 122 to the arm 115, the upper end of which is struck up in form of a box, in the sides of which are the bearings of the stop-rod. The sides of the box are extended and turned out, as at 123, the turned- 85 out ends being screwed to the rack-bar of the carriage. When the carriage is free, therefore, it may be moved in either direction by manipulation of the arms extending to the front by the side of the keyboard. The arm 90 95 115 has an offset 115^x fitting over the shaft of the spring-tightening device, on which is the knob 124. The shaft of this knob carries a ratchet-wheel 125 outside of the plate 126, which covers the rear of the machine, and this ratchet-wheel has an escapement-lever 127, provided with a finger-piece. The shaft passes through the back bar of the carriage-frame, and upon it near the forward end is the pulley 128 loose on the shaft, but held by 100 means of a collar 129 against endwise movement. The pulley is provided with a case 130, in which is a coiled spring, one end of 105 which is secured to the case and the other to the shaft.

110 The tension of the spring may be increased by turning the knob to the right, or may be diminished by manipulating the escapement-lever.

The shaft abuts end to end against the 115 shaft 76^x, which carries the pinion 76, hereto, fore described, which drives the ribbon-spools- and the shell 130 is connected to the ribbon-shaft by a pawl-and-ratchet connection, the pawl being carried by the shell 130 and the 120 ratchet by the shaft 76^x, so that the movement of the carriage to the left is accompanied by a movement of the ribbon-shaft, which remains stationary when the carriage moves to the right.

125 The escapement-pawls 131 132 are mounted upon an eccentric-screw set in the standard 131^x on the carriage-bed. They are provided with springs and pins 133 134, which extend over a wiper or cam plate 135. This has one 130 high part for one pin and another for another, marked, respectively, 136 137, so arranged that one pawl is always held out of engagement with the rack-bar. The high parts, however,

are so arranged and shaped, as shown in Fig. 4, that by certain lesser amount of movement of the cam-plate the alternate escapement motion of the two pawls is secured, but by a greater movement to the left of the cam-plate both pawls are released and the carriage is set free. The cam-plate, which is in the form of a broad blade, is carried upon an upright arm on a bell-crank lever 138. Another arm 139 of this lever is connected to the retracting-spring, which causes the cam-plate to retreat to the right.

The horizontal arm of the bell-crank lever 138 extends over an arm 141 on a rock-shaft 142. This rock-shaft has arms 142^x projecting forward connected to the bar 142^a, which extends under the key-levers. The key-levers appropriate to the printing-characters depress this bar only enough to operate the escapement, but there is a key-lever on the right of the machine, 143, which has a greater range and will depress the bar far enough to fully release the pawls, as before explained. On the left of the keyboard is the finger-piece of a key-lever 144, which is connected by a link 144^x to an arm 145 on a sleeve which carries an arm 146, the sleeve being supported upon a stud on the carriage-bed. The arm 146 extends under the frame 105, which carries the pawl operating the line-feed, and by the manipulation of this key-lever the paper-roll may be operated at will and independently of the automatic mechanism above described.

I have provided means for adjusting the spring 135^x which returns the cam-plate operating the escapement-pawls of the carriage, and thus for varying the amount of pressure required to operate the keys of the type-levers. This consists of a screw connection and thumb-piece 147 on the left-hand side of the machine; by means of this the tension of the spring upon the bell-crank lever which carries the cam-plate may be varied.

I have in front of the bank of keys an ordinary spacing-bar which operates the escapement in the ordinary way.

It will be observed that the type-bars are formed with thicker rear ends and thinner at the forward ends and are provided with horizontal flanges on the lower edge. These horizontal flanges form a broader bearing and also fit into lateral notches in the guide-plates, so that they are held securely against displacement. I have provided a special construction for the pins which are set in the type-bars and in the bell-crank levers for the removable link which connects these parts. The pin is shown enlarged in Fig. 18. It has a peripheral groove 150 a little aside of the center, and when this pin is inserted in the lever or bar the metal is struck up into the groove, as shown in the figure, so that the pin is held therein with very little trouble and expense.

It will be seen from Fig. 2 that the links 12 and 13, which operate the type-bar levers, are arranged radially in relation to the pivot 45 of the type-bar frame, and when the frame is

tilted on the pivot 45 to change from upper to lower case there will be no tendency for the operating connections—*i. e.*, the links and the type-bar levers—to be changed in relation to each other nor no straining or tension will be placed on the parts. The nose of the bell-crank lever is also so arranged and constructed that it will be impossible for the link to become detached therefrom, and in linking or unlinking the machine it is necessary that the type bars and levers be at their extreme limit rearward before the links can be attached or detached, the said links merely resting in the hook of the nose and having no pivot-pin connection therewith.

The roller-frame 151, upon which the paper-carriage works, I have found must be of special construction to avoid binding of the same on the stationary ways 81 82. This roller-frame is shown in Figs. 2 and 12, and consists of two side bars 152, a connecting-bar 153 at one end, and the rollers 154. I have found that it is necessary that one of the side bars 90 must be rigidly fixed to the cross-bar, and in the drawings I have shown the rigid connection as effected with solder at *y*, though I do not limit myself in this respect, as the rigid connection may be made in some other way. 95 This form of frame keeps the rollers in line and prevents “creeping” of one roller in advance of the other, which would result in binding of the roller-frame and carriage. The roller-frame has two spurs 155 struck from one of 100 the side bars, and these are in line with a pin 156, shown in dotted lines in Fig. 2 as depending from the front bar of the carriage-frame, so that should the roller-frame get out of its proper position relative to the carriage-frame, the pin on the carriage will move the frame into proper relative position.

The stop-bars 20 and 21 for the type-bar levers are held to the machine by spring-arms 20' 21', which are attached to the stop-bars by 110 the ends of the bars which project beyond the rubber tubing entering openings in the spring arms or clips, so that it is only necessary in order to remove the stops to press back the spring-arm at either end of the bar and 115 remove the same. The projecting ends are squared off on one side at 20' 21' to fit the holes in the clips.

The rear one of the type-bar guide-plates 34 has notches 34' in its edges for the type-bars of the upper and lower case, as before stated, and these notches are of the peculiar form represented in Fig. 9—that is, the vertical portion of the notch 34' is enlarged laterally at 34" and the type-bars have lateral 125 ribs 34^a corresponding thereto. The notch and type-bar are relatively proportioned so that the type-bar may have lateral play, but the ribs fitting in the lateral enlargements of the notches will be guided accurately against 130 vertical displacement. The openings in the guide-plate 33 are merely plain slots and do not have any effect to hold the type-bars against free lateral play, excepting by their

end walls, which confine the outer type-bars of the set and those in turn confine the next inner type-bars, and so on throughout the set, it being understood that the type-bars are so fitted to the slots as to permit lateral play of the said bars to prevent sticking, and these guide-plates are not depended on to guide the type-bars laterally, but for this purpose the converging guide-plates 53 and the shifting 5 guide-tongue 55 are used. The said tongue is held pivotally in place by merely notching its upper and lower arms and fitting them to the edges of the slot in the plate 33.

The pawls 131, 132 of the escapement are, 15 as before stated, carried by the standard 131^x, and this is pivoted at 131^a to the machine-frame, and is under tension of a spring 131^b, connected thereto and to the cross-bar 131^c, extending between the ways 81, 82. This spring 20 tends constantly to force the standard and hold it against a stop 160. The purpose of this arrangement is to provide a support for the pawls which will be perfectly rigid while the step-by-step movement of the carriage from 25 right to left is taking place, and which will yield and allow the pawls to yield when they are returned into engagement with the carriage after the carriage has been released and has acquired considerable force and 30 momentum in its free passage from right to left. The standard 131^x is also held rigidly against the stop 160 by the spring when the carriage is thrown to the right for beginning a new line, as the strain or shock on the pawls at this time 35 is no more than that resulting from the ordinary step-by-step movement.

I have provided an arm 161, Fig. 2, connected with the shaft 142 and extending up in the range of the paper-clip, so that when 40 the paper-clip comes opposite this arm the arm will strike the clip and act as a lock to the depression of any key and to prevent the release of the escapement. As the shaft 142 is moved by the universal space-bar 142^a at each key action, it follows that the arm 161 is also moved, and as the shaft 142, with its arm 141, controls 45 the escapement, the striking of the arm 161 against the paper-clip when the latter comes before it will prevent the escapement from 50 working, and also prevent the depression of the keys. In order to prevent the movement of the clips past the printing-point, an arm 162 projects inwardly from the frame, and in the same vertical plane as the printing-point, 55 and in line with the paper-clip to strike the same and prevent them from extending over the printing-point. The carriage is operated from the pulley 128 by the cord 128^a.

The adjustable stop 111 is made from a single 60 blank, (shown adjacent to Fig. 4,) said blank having the body portion and the tongue 111^x. The blank is struck up on the dotted lines, shown so as to make the body portion of channel or U shape in cross-section, the tongue or 65 spur 111^x being struck up at the same time. This provides a cheap and efficient form of stop. This stop-piece has the rear end of its

upper flange bent down to form the pawl-tooth for engaging the rack, and a leaf-spring (indicated in Fig. 4) between the lower flange and 70 the lower edge of the rack holds the stop-piece against movement longitudinally of the rack. The said channel-stop is retained in place between the rack and the rear side of the carriage by the rack-bar extending through its 75 channeled face.

The pawls of the escapement, as shown in Fig. 3^a, are held by an eccentric screw 131^x, and by turning this screw the pawls may be adjusted in relation to each other. 80

The object of this adjustment is to get the spaces between the letters of the proper size to suit the type.

What I claim is—

1. In combination, the longitudinally-mov- 85 able converging type-bars, converging fixed guides therefor, a platen, and a swinging guide between the fixed guides converging therewith and adapted to be thrown from side to side of the guideway by the impact of the 90 type-bars, substantially as described.

2. In combination with the longitudinally- 95 moving type-bars and the fixed guides near the platen, an auxiliary movable guide ar- ranged between the walls of the fixed guide 100 and adapted to divide the space thereof and to form with either guiding-wall a smaller guiding-space, substantially as described.

3. In combination with the converging type- 105 bars having their heads arranged squarely to the platen, the converging guide-plates having their rear ends near the platen with an open space between the said ends adapted to receive the head of the type-bars and an aux- 110 iliary guide supported at its front end upon the cradle-frame with its rear end arranged between the front end of the converging guides and converging therewith to divide the space of the main guide up and to make a small tapering guide-space, the said auxiliary 115 guide being adapted to shift freely from side to side of the main guides, substantially as described.

4. The cradle-frame composed of a single 120 casting carrying guide-plates for the type-bars and having integral arms extending to the front and to the side of the keyboard and upwardly-extending standards pivoted at their upper ends, arms extending rearward from the central portion of the upright stand- 125 ards, said forwardly-extending arms being connected to the lower ends of the upright standards, substantially as described.

5. The reciprocating type-bars having pins and the bell-crank levers for operating said 130 type-bars having pins and combined with connecting-links having a rigid center and spring ends on each side thereof, said ends being perforated to fit over the pins of the type-bars and levers, substantially as de- 135 scribed.

6. The connecting-link for the levers and type-bars formed of a single piece of sheet metal having a central connecting part bent

as described into **U** form in cross-section and elastic ends in combination with said levers and bars, said ends embracing the levers and the type-bars substantially as described.

5 7. In combination, the reciprocating type-bars, the levers and the links having **U**-shaped central portions embracing the upper edges of the bars and having spring ends embracing the bars and levers and sprung into connection therewith, substantially as described.

10 8. In combination, the platen, the type-bars of the upper and lower case, the key-levers with connections thereto, the rocking cradle-frame, and the stops therefor, consisting of the eccentric disks, and the buffers held thereby, with means for clamping the disk in any adjusted position, substantially as described.

15 9. In combination, the platen, the sliding type-bars, the guide-plates 34, 33, said plate 33 having the plain slots and the plate 34 the notched slots, said notches having lateral extensions to receive ribs on the type-bars to hold the bars against vertical movement while 25 the plain slots allow the bars to move laterally, substantially as described.

10 10. In combination, the platen, the converging type-bars, the converging guides for directing the type laterally, and the shifting tongue working from side to side intermediate of said guides and converging therewith, substantially as described.

15 11. In combination, the platen, the converging type-bars, the guide-plate having the slots for the bars, and the shifting tongue for guiding the type-bars said tongue having notches engaging the guide-plate, substantially as described.

20 12. In combination, the type-bars, the cradle-frame having the arm 35 extending forwardly therefrom and having the downwardly-projecting lug 44, the lever 38 having an arm 39 to bear on the under side of the lug 44 to move the arm 35 of the cradle-frame 45 downwardly, and the spring 40 arranged to hold the lever 38 in either position, substantially as described.

25 13. In combination, the platen, the end frames carrying the same, the ratchet-wheel, 50 the pawl-lever operating vertically, the line-space frame carrying the pawl-lever and journaled in the end frames, said end frame having a laterally-extending arm at its upper part, having two stops between which the upper end of the vertically-moving pawl-lever operates, and the spring for drawing the pawl-lever laterally into contact with the ratchet-wheel.

30 14. In combination, the platen, the end frames carrying the same, the ratchet, the pawl-lever for engaging the same, the laterally-extending arm 104 on the end frame having stops on its inner side to engage and control the pawl-lever and the line-space regulator pivoted on the inner side of the end frame and having a portion to shield the ratchet from the pawl-lever, said line-space

regulator being bent over the arm to its outer side and terminating in stops embracing the said arm, substantially as described.

70

15 15. In combination, the type-levers, the carriage and platen, the line-space mechanism including the line-space frame 105 on the front of the carriage, connections therefrom to one of the keys, the pawl carried thereby, 75 said space-frame having a rearwardly-extending arm 108, an adjustable stop in rear of the carriage on the main frame, the bar 110 movable longitudinally of the carriage and adapted to strike the stop, and the lever 109 between the bar 110 and the extension 108 of the space-frame, substantially as described.

20 16. In combination, the platen, the carriage, and the escapement mechanism comprising the rack-bar, the two pawls arranged side by 80 side extending in the same direction and having pins projecting laterally therefrom at different distances from the pivot of the pawls and a single wiper-arm pivoted at its lower end to swing longitudinally of the pawls and 85 having its upper end in the form of a broad blade the upper edge of which is of cam form and engages the projecting pins of both pawls, substantially as described.

25 17. In combination, the platen, the carriage, 90 the escapement comprising the two pawls and a single wiper, having cams to operate both pawls, a carriage-releasing key-lever arranged to operate the wiper to cause the high part thereof to release both pawls, substantially 95 as described.

30 18. In combination, the platen, the carriage, means for returning the carriage to normal position when released, the escapement comprising the pawls, and the cam-wiper for operating and releasing both pawls, said pawls being yielding under the impact of the released carriage, substantially as described.

35 19. In combination, the platen, the carriage, 100 means for moving the carriage automatically when released and the escapement comprising the pawl and stop-detent and the yielding standard carrying the same to give under the impact of the carriage, substantially as described.

40 20. In combination, the bell-crank levers and the pins held therein, said pins having a recessed body portion into which the metal of the lever is pressed, substantially as described.

110

45 21. In combination, the type-bars and the links **U**-shaped in cross-section having a pair of spring-arms at each end, substantially as described.

115

50 22. In combination, the platen, the type-bars for the upper and lower case letters, the swinging frame pivoted to the main frame, the bell-crank levers the key-levers and the links connecting the same with the bell-crank levers, said links extending in a direction substantially radial from the pivot of the swinging frame, substantially as described.

120

55 23. In combination, the carriage-frame, the platen, the paper-clips and the paper-shelf, en-

125

130

gaging the end frames of the carriage and held by the paper-clips against the same, substantially as described.

24. In combination, the carriage, the escapement-pawl and rack, the rock-shaft 142, the arm 141 extending therefrom connections to the escapement-pawl, the key-levers, the frame 142^a operated thereby, the connection therefrom to the rock-shaft consisting of the link 144^x and the arm 142^x, the paper-clip on the carriage, and the arm 161 of the rock-shaft to engage the paper-clip.

25. In combination, in a type-writer, the platen, the carriage, the adjustable paper-clips, the key-levers and the lock-arm 161, operated by the key-levers to engage the clip and lock the key-levers against action when the clips come opposite the said arm, substantially as described.

26. In combination, the carriage, a rack-bar in rear thereof held with a space between it and the carriage and a stop on the rack-bar

consisting of the channel-piece having its upper and lower flanges embracing the rack-bar, the rear end of the upper flange being bent 25 down to form the pawl-tooth of the stop, and a spring between the lower flange and the lower edge of the rack-bar, said channel-piece being retained in place by the rack fitting into its channeled face and by the rear side 30 of the carriage between which and the rack-bar the channeled piece extends, substantially as described.

27. In combination, with the carriage and rack, the escapement-pawl and the eccentric 35 screw-pin for holding and adjusting the same, substantially as described.

In testimony whereof I affix my signature in presence of two witnesses.

BERNARD GRANVILLE.
